UNITED STATES PATENT OFFICE.

WILLIAM H. CONNELL, OF PITTSBURGH, PENNSYLVANIA.

CASTING APPARATUS.

1,074,250.

Specification of Letters Patent. Patented Sept. 30, 1913.

Application filed November 1, 1912. Serial No. 729,084.

To all whom it may concern:

Be it known that I, WILLIAM H. CONNELL, residing at Pittsburgh, in the county of Allegheny and State of Pennsylvania, a citizen 5 of the United States, have invented or discovered certain new and useful Improvements in Casting Apparatus, of which improvements the following is a specification.

The invention described herein relates to 10 the teeming of metal into ingots, especially with relation to the formation of compound ingots, *i. e.*, ingots having portions formed of different kinds and grades of metal, and the said portions meeting in flows in opposite 15 directions and merging one into the other, both metals being simultaneously teemed into the mold.

In simultaneously teeming the metals into the mold from ladles at considerable distances 20 above the mold, through orifices in the bottoms of the ladles and with considerable depth of metals in the ladles, the momentum acquired by the metals falling under these conditions produces, when the 25 metals meet in the mold flowing in opposite directions, such agitation as to broaden and render irregular the zone of merger which it is desired shall be vertical and of small lateral area, in order that large portions of the 30 ingot shall be the same in quality as the metal in the ladle from which the respective portions are poured.

The invention described herein has for its object the separation of the metal to be 35 charged into the mold into a plurality of relatively small streams, and the retardation in the rate of flow without diminishing the quantity of metal delivered into the mold in a given time.

40 It is a further object of the invention to provide for the heating of the distributer and thereby preventing the accumulation of solidified metal on the walls and in the outlets of the distributer.

45 The invention is hereinafter more fully described and claimed.

In the accompanying drawing forming a part of this specification, Figure 1 is a top plan view of my improved distributer; Figs. 50 2 and 3 are sectional views, the planes of section being indicated respectively by the lines II-II and III-III, Fig. 1.

In the practice of my invention the distributer consists of an outer shell 1 preferably formed of metal and a lining 2 of refractory material. As the bottom of the

shell is inclined upwardly from a median line, shoulders 3 are preferably formed thereon to insure a good bearing on the end of the mold. The receptacle is divided into two compartments by a transverse partition 4 and through the bottom of each compartment are formed outlets 5 and 6, which are preferably so arranged that the several streams of metal will enter the mold at 60 points adjacent to the corners, and therefore as widely separated as possible. As will be seen by reference to the drawings, the bottoms of the compartments are so constructed that the surfaces incline toward the outlets, 65 thus insuring a complete discharge of the metal.

In order to prevent the walls and outlets of the distributer becoming clogged by solidified metal, a roof 7 is arranged to cover 70 the distributer except at the ends at which the metals are teemed into the distributer. While this roof, which has its undersurface protected by refractory material will reflect the heat onto the metal flowing through the 75 compartments thus preventing a large loss by radiation, it is preferred that its undersurface should be raised to a temperature approximately that of the molten metal. To this end a suitable electrical resistor 8, such 80 as carbon or a suitable metal is incorporated in the roof and adapted to be connected to a suitable generator.

While my improvement is adapted to simultaneously direct the metal from two 85 ladles, which may contain the same kind or grade of metal, thus reducing the time heretofore required in filling the mold, it is especially adapted for making compound ingots containing two different kinds or 90 grades of metal which are teemed into the distributer from separate ladles. The proportions of the different kinds of metal to be used, are regulated by the relative dimensions of the outlets 5 and 6. In the construction shown the outlets 5 have a delivery capacity two and one third times that of the outlets 6 and the completed ingot will consist of 70% of one kind of metal and 30% 95 of the other.

100 It is characteristic of my improvement that the maximum speed acquired by the metal falling into the mold will at no time exceed the square of height of the mold and that such rate will diminish as the metal rises in the mold. It is also characteristic 105 of my improvement, that the respective

quantities flowing into the mold are not dependent on the relative quantities teemed into the distributor provided of course sufficient metal is poured into the compartments 5 to fully compensate for the outflow through the outlets 5 and 6. Hence by properly proportioning the outlets 5 and 6 relative to one another, it can be made certain that each one of a series of ingots will have the same relative amounts of metal as all the other ingots of the series.

I claim herein as my invention:

1. A metal distributor movable from mold to mold, having in combination independent 15 chambers or compartments for the reception of metal, each compartment having a plurality of separated outlets.

2. A metal distributor movable from mold to mold, having in combination independent 20 chambers or compartments for the reception of metal, each compartment having a plurality of separated outlets, the outlets from one compartment having a combined delivering capacity greater than the combined

capacity of the outlets from the other compartment.

3. A metal distributor, having in combination independent chambers or compartments, each compartment having an outlet, and a roof arranged above the compartments and 30 adapted to reflect back the heat radiating from the metal flowing through said compartments.

4. A metal distributor, having in combination independent compartments or chambers, each compartment provided with an outlet, a roof arranged above the compartments and adapted to reflect back the heat radiating from the metal flowing through 35 said compartments, and means for applying 40 heat to the surface of such metal.

In testimony whereof I have hereunto set my hand.

WILLIAM H. CONNELL.
